UNITED STATES PATENT OFFICE.

JAMES D. BENBOW, OF AURORA, ILLINOIS, ASSIGNOR TO WESTERN WHEELED SCRAPER COMPANY, OF AURORA, ILLINOIS, A CORPORATION OF ILLINOIS.

ELEVATING GRADER.

Application filed May 28, 1924. Serial No. 716,481.

To all whom it may concern:

Be it known that I, JAMES D. BENBOW, a citizen of the United States, and a resident of Aurora, in the county of Kane and State 5 of Illinois, have invented certain new and useful Improvements in Elevating Graders, of which the following is a specification, reference being had to the accompanying drawings.

10 This invention relates to grading machines of that type employing an endless conveyor belt that projects to a considerable distance at one side of the main frame of the machine and upon the lower portion of which 15 belt the soil turned up by the plow that is carried by such frame is deposited and carried upward and discharged over the upper end of the elevator. The object of the invention is to provide improved means adjacent to the lower end of the elevator whereby the bearings or boxes for the roller at the lower end of the elevator and over which the 20 endless conveyor belt runs are supported so as to be adjusted as required longitudinally 25 of the elevator for the purpose of holding the belt in properly stretched condition, and in connection with such adjusting means to provide a pan arranged to catch dirt, pebbles, trash, &c., and having scrapers for 30 moving such matter from the roller and belt, so that it will be caught on the pan, and in that way effectually prevent such matter from being carried between the said belt and 35 roller and thus save the belt from injury, such parts being so arranged and combined 40 that an adjustment of such bearings or boxes will also result in a simultaneous adjustment of the pan and the scrapers carried by it, or the pan with the scrapers can be independently adjusted. This object I accomplish as illustrated in the drawings and as 45 hereinafter particularly described. That which is believed to be new will be set forth in the claims.

45 In the drawings,—

Fig. 1 is a side elevation of the lower portion of an elevator for a grading machine, with which is embodied the invention;

50 Fig. 2 is an enlarged view partly in vertical section, and showing perspectively the lower end portion of the elevator,—the section being taken at line 2—2 of Fig. 4;

55 Fig. 3 is an enlarged detail taken at line 3—3 of Fig. 4, and showing the relation of the pan and its scraper members to the end-

less conveyor belt and the lower roller that the belt passes over;

Fig. 4 is a view partly in plan and partly in longitudinal section, the section being taken at line 4—4 of Fig. 1, some of the 60 parts being broken away;

Fig. 5 is a cross-section taken substantially on the line 5—5 of Fig. 1;

Fig. 6 is a perspective view of the pan and the scraping members carried thereby; 65

Fig. 7 is a perspective view of one of the two side members at the lower end of the elevator upon which are supported the adjustable bearings or boxes for the lower belt-roller; and 70

Fig. 8 is a perspective view of one of the adjustable bearings or boxes for the lower belt-roller.

Referring to the several figures of the drawings,—10 indicates the lower portions 75 of the side bar members of the frame of an elevating conveyor that is movably supported from the wheeled supporting frame of an excavating machine, as usual, and projects across such frame to a considerable distance 80 so that earth deposited upon the endless conveyor belt member of the elevator by the action of the plow that is carried by said main wheeled frame will be moved upwardly and discharged at one side of the line of travel 85 of the machine—all as is well understood. The endless conveyor belt referred to is indicated by 11 and will be driven in any usual manner. Ordinarily, such driving of the belt will be by means of gearing connected with one of the main wheels of the machine and sprocket wheels and a sprocket chain, such chain engaging over a sprocket wheel carried by the outer or upper drum or roller (not shown) of the elevator. I have 90 not deemed it necessary to show any driving means for the belt, as such means are well understood and may be of any usual construction and arrangement. Secured to each of the side members 10 of the elevator frame, and located at intervals therealong, are brackets 12 that overhang the marginal portion of the upper run of the belt and have secured to them wide plates 13 that form 95 side boards for retaining on the belt 11 the dirt that the belt is carrying for delivery from the upper end of the elevator.

At the lower end of each of the side bar members 10 of the elevator frame and forming in effect extensions of such side bars 100

are heavy blocks 14 the smooth upper faces of which form seats upon which rest and are secured the adjustable boxes or bearings hereinafter referred to. Each of these blocks 14 has at its forward end a heavy extension 15 that lies against the outer face of one of the side bar members 10 and is bolted thereto by bolts 16, as clearly shown in Fig. 2. At the forward end of each of the blocks 14, which is the higher end when the elevator is in operative position as shown, is a short flange 17 that stands at right angles to the smooth upper face of the block, and through such flange is a tapped opening 18 that receives a bolt 18. Lying on the flat upper surface of each block is a heavy plate 19 that has formed with it a journal box or bearing 20 that receives the reduced cylindrical end of a heavy roller 21 around which the endless conveyor belt 11 passes. A suitable removable bushing 22 of brass or other material is preferably employed in each bearing. The plate portion 19 of each bearing member is provided with one or more longitudinal slots 23—two such slots being shown—through each of which a bolt 24 passes, the stem of each bolt also lying in a notch 25 formed in the outer edge of the upper part of a block 14. The head of each bolt 24 engages under the top or plate portion of the block, and nuts 26 on such bolts, when turned down against the surfaces of the plate members 19 of the bearings, will hold such bearings firmly in place. It is evident that with the several nuts 26 loosened sufficiently the two bearings can be adjusted so as to cause the desired tightening of the belt, and such movement for belt-tightening purposes is had by turning the screws 18 that pass through the flanges 17, each of such screws bearing against an upstanding lug 27 formed with the plate member 19 of each box or bearing 20. The notches 25 in the sides of the blocks 14 permit the bolts 24 to be readily inserted in or removed from position.

Resting upon the inner edges of the two plate members 19 of the respective boxes or bearings is a metal plate 28 which is termed a dirt pan because of the fact that dirt scraped from both the roller 21 and inner surface of the upper run of the conveyor belt will be deposited thereon as hereinafter described. Such dirt pan is secured in place to each of the members 19 by bolts 29 and nuts 30 screwed thereon. These bolts project up through suitable holes in the inner marginal portions of the respective members 19 and pass through slots 31 that are formed in the dirt pan adjacent to the side edges thereof, as clearly shown in Fig. 2. It is evident, therefore, that when the bolts 30 are tightly set any adjustment of the bearings for the purpose of regulating the tension on the conveyor belt will at the same time correspondingly move the dirt

pan, but as it is sometimes desirable that the dirt pan be given an adjustment independent of the adjustment of the bearings the slots 31 in the dirt pan are provided, and it will be evident that by loosening the nuts 30 such independent adjustment can be readily had. At that edge of the dirt pan adjacent to the roller 21 it is provided with a scraper 32 that is here shown as a strip of angle iron, one flange of which is adapted to rest in contact with the surface of the roller, the other flange resting upon the upper surface of the dirt pan and being riveted thereto.

Adjacent to the opposite edge of the dirt pan is another scraper member 33 that rises sufficiently high from the pan to bring its upper edge in contact with the lower face of the upper run of the conveyor belt 11. Such scraper member 33 is here shown as a flat plate that is held in place by being riveted to an angle-iron 34 which latter is also riveted to the dirt pan. For stiffening purposes I preferably provide against the outer face of the member 33 a metal strip 35 that is secured by the same rivets that rivet the member 33 to the angle-iron 34. Both of the scraper members 32 and 33 extend across the elevator so as to scrape the entire surfaces of the moving parts that they are in contact with. It is because of the necessity for setting the dirt pan in exactly the right relative position with respect to the roller 21 so that the scraper member 32 will operate effectively on it that the pan is made adjustable independently of the adjustment of the bearings for the roller 21. After such relative position has been secured, then it will not ordinarily be necessary to independently adjust the pan, although such independent adjustment can be readily and quickly performed at any time if required. It will be evident that with the parts in position as described, and with the belt moving in the direction indicated by the arrow in Fig. 2, any dirt will be prevented from adhering either to the surface of the roller or the inner surface of the upper run of the belt, which very materially aids in preventing injury to the belt that might readily occur if pebbles or other hard substances were allowed to be carried between the belt and the roller. The contacting with the roller and the belt by the members 32 and 33 effectually prevents such injury, and any dirt, pebbles or other matter that may be scraped off of these moving parts will drop onto the pan, and the upturned member 32 at the lower end of such pan will prevent such matter from sliding off the pan and getting between the roller and the belt.

To ensure the two blocks or bearing members 19 being held more rigidly together, I provide a tie-rod 36 that extends between

them and has its ends inserted through holes in upstanding ears 37 carried by the members 19, nuts 38 being screwed upon the projecting ends of such rods. A tubular 5 spreader 39 surrounds this rod between the ears 37.

40 indicates a shoe, here shown as a wide heavy metal plate which extends across the lower end of the elevator and projects beyond the sides thereof, as usual. Such shoe is bolted to the under sides of the two blocks 14 and to this shoe is adapted to be connected a brace rod (not shown) that extends to and is secured to the main frame 15 of the grading machine. The means for raising the elevator as a whole so as to vary its inclination, and rollers for furnishing a support for the intermediate part of the belt are shown in part, but they, as well as other features of construction, are not here described because they are features in common use in machines of this character and their construction and operation will be understood by those familiar with such machines.

By my invention I provide readily accessible means whereby the boxes or bearings for the lower roller over which the endless conveyor belt travels can be readily 30 and quickly adjusted so as to compensate for any stretching of the belt that occurs from use, and also provide other means that are equally accessible for adjustably securing in place the devices that prevent any matter passing between said roller and belt that would tend to injure the belt.

What I claim as my invention and desire to secure by Letters Patent, is—

1. An elevator for elevating graders comprising, in combination, a frame, an endless belt, a roller adjacent to one end of said frame over which roller said belt passes, supporting means for said roller movable longitudinally of said elevator frame to adjust the tension of the belt, and a dirt pan adjustable relatively to and movable with said supporting means.

2. An elevator for elevating graders comprising, in combination, a frame, an endless belt, a roller adjacent to one end of said frame over which roller said belt passes, supporting means for said roller movable longitudinally of said elevator frame to adjust the tension of the belt, a dirt pan ad-

justable relatively to and movable with said supporting means, and a scraper carried by said pan and operating to remove dirt from said roller.

3. An elevator for elevating graders comprising, in combination, a frame, an endless belt, a roller adjacent to one end of said frame over which roller said belt passes, supporting means for said roller movable longitudinally of said elevator frame to adjust the tension of the belt, a dirt pan adjustable relatively to and movable with said supporting means, and a scraper carried by said pan and operating to remove dirt from said belt.

4. An elevator for elevating graders comprising in combination a frame, an endless belt, a roller adjacent to one end of said frame over which roller said belt passes, adjustable belt-tensioning means, a dirt pan connected with said tensioning means and 75 adjustable with the same and also adjustable relatively thereto, and separate means for respectively holding said tensioning means and said dirt pan in their different adjusted positions.

5. An elevator for elevating graders comprising in combination a frame, an endless belt, a roller adjacent to one end of said frame over which roller said belt passes, adjustable belt-tensioning means, a dirt pan 85 connected with said tensioning means and adjustable with the same and also adjustable relatively thereto, separate means for respectively holding said tensioning means and said dirt pan in their different adjusted 90 positions, and means carried by and adjustable with said dirt pan and normally in scraping contact with said roller.

6. An elevator for elevating graders comprising in combination a frame, an endless belt, a roller adjacent to one end of said frame over which roller said belt passes, adjustable belt-tensioning means, a dirt pan connected with said tensioning means and adjustable with the same and also adjustable relatively thereto, separate means for respectively holding said tensioning means and said dirt pan in their different adjusted 100 positions, and means carried by and adjustable with said dirt pan for respectively 105 contacting with the roller and with the inner surface of the belt.

JAMES D. BENBOW.
